UNITED STATES PATENT OFFICE.

FREDERICK KERSHAW, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

PROCESS OF CONDITIONING AND COOLING YARN.

Application filed May 6, 1928. Serial No. 107,296.

One object of my invention is to improve the process of conditioning and cooling yarn, whereby the yarn, as it comes from the drier, is first subjected to a steam or hot water spray, and then subjected to cold water sprays to cool the yarn before it leaves the apparatus.

A further object of the invention is to improve the process of drying by separating the hanks of yarn to allow the sprays to gain access to all portions of the hanks, and thus more uniformly humidify the yarn in a shorter period of time.

In the accompanying drawing:
 15 Fig. 1 is a sectional view of the apparatus illustrating my improved method of conditioning and cooling yarn; and
 20 Fig. 2 is a sectional view on the line 2—2, Fig. 1.
 25 While I have shown one form of apparatus and a certain arrangement of the frames, circulating passages, and heating system, the apparatus may be modified materially without departing from the essential features of the invention.

1 is the casing of the apparatus, enclosing in the present instance two drying compartments 2—2, a circulating warm moistening compartment 3, and a cool moistening compartment 4. These compartments are separated by vertical partitions 5, having openings for the passage of a conveyor and the yarn carried thereby.

At the side of each compartment 2, 3 and 4 is a circulating compartment, one compartment being separated from the other by a vertical transverse partition 5 and from the compartments 2, 3 and 4 by a vertical longitudinal partition 7, in which are 40 openings for the circulating fans 6 of the usual type. In each of the circulating compartments at the sides of the compartments 2, 2 and 3 are heating coils 8.

9 are conveyor chains of the usual type, and extending from one conveyor chain to the other are poles 10, on which the hanks of yarn *a* are suspended. These hanks of yarn are usually spaced close together and they remain in this condition while passing 50 through the drying compartment 2—2 in order to properly condition the yarn. When the hanks of yarn are close together, it is difficult to produce a uniform conditioning of the yarn in a short period of time with-

out obtaining an excess of moisture at the ends of the skeins. This is caused by the fact that the air is filled with minute particles of moisture, and the yarn itself acts as a strainer, that portion of the yarn upon which the air strikes first receiving a greater portion of the moisture.

In order to prevent this, a transverse retarding-bar 11 is located in the warm moistening compartment 3 in the path of the lower ends of the hanks of yarn, so that as the hanks of yarn pass the bar they are held back in order to form an opening *b*. Directly below the opening *b* is a spraying device 12 having a series of nozzles, and this spraying device in the present instance is connected with a steam supply pipe 13 and a drip pipe 15, although hot water may be used instead of the steam.

This spraying device projects sprays into the open space *b*, and the entire length of the hanks on either side of the opening are directly subjected to the spray. In this way the yarn is more uniformly humidified in a shorter period of time than heretofore.

In the compartment 4 there is another retarding-bar 11^a and a cool water spraying device 14 which is connected to a water-pipe 16 and an air-pressure pipe 17. The air is used as a medium for atomizing the water. This cool water spray furnishes an additional amount of humidity and at the same time furnishes a valuable cooling effect, so that the yarn, after coming from the drier and conditioner, will be cool and retain its moisture.

The mechanism disclosed in this application is fully set forth and claimed in the patent granted to me on June 1st, 1926, No. 1,587,384, the present application being limited to the process.

I claim:—

1. The process herein described of drying or conditioning yarn, said process consisting in conveying the hanks of yarn through a drying compartment, then through a conditioning compartment, retarding one hank of yarn after another as it passes through said conditioning compartment, and spraying the separated hanks to moisten the same.

2. The process herein described of conditioning and cooling yarn, said process consisting in conveying the hanks of yarn first through a drying compartment, then

through a warm moistening compartment, 5 retarding one series of hanks after another in said compartment so as to separate the hanks, subjecting the hanks of yarn while separated to the action of a warm moistening spray, then passing the same through a cool moistening compartment, and then subjecting the separated hanks to the action of cool water sprays.

3. The process herein described of drying or conditioning yarn or similar material, said process consisting in conveying hanks of yarn through a drying compartment, then moistening the yarn after it leaves said compartment, and finally subjecting the 15 yarn to cool water sprays.

FREDERICK KERSHAW.
